HARNESS CONNECTION FOR LOOMS

Henry Lussier, Salem, Mass.

Application February 23, 1933. Serial No. 657,942

3 Claims. (Cl. 139—88)

This invention relates to improvements in loom shedding apparatus and particularly to means for connecting the treadle or other harness actuating means to the harness.

To produce a woven fabric of uniform texture and appearance, the loom upon which it is made must function smoothly and accurately. Each element of the loom must be properly adjusted and maintained positively in adjustment. Particularly is it essential to insure the accurate and uniform function of the shedding mechanism. Any irregularity in the operation of the shed forming mechanism varies the tension in the warp and results in an uneven beat-up causing irregularity in the fabric. It becomes highly important, therefore, to maintain the shed absolutely uniform, and such uniformity depends directly upon the invariable length of the harness connectors. A common construction employs leather straps for such connectors which are subject to a great deal of maladjustment due to stretching, slipping, etc.

It is the chief object of the present invention to provide a harness connector which will eliminate defects in the fabric due to maladjustment of the shedding mechanism.

The object of the invention is further to provide a harness connector which when adjusted may be locked positively in adjusted position.

The object of the invention is further to provide a connector which is adaptable to and may be substituted for existing equipment upon the loom.

The object of the invention is further to provide a connector having two separate and independently operable adjustments, one of which provides a quickly and readily made approximate adjustment and a supplemental adjusting means capable of readily making changes for fine adjustments regardless of the degree of tension already existing in the harness connecting elements.

Other objects and features will more fully appear from the following description in connection with the accompanying drawing and will be particularly pointed out in the claims.

In the drawing:

Fig. 1 is a side elevation of the device showing a portion of the elements of the loom to which it is connected.

Fig. 2 is a front view of the elements shown in Fig. 1.

Fig. 3 is an enlarged sectional detail view on the line 3—3, Fig. 1.

To present a clear and accurate understanding

of the invention, a particular embodiment thereof will be set forth herein.

The invention preferably is designed to connect the usual treadle 1 and the harness 2. The treadle may be operated by cams which are not illustrated or by any other suitable harness actuating means, such as a dobby or similar mechanism. The harness is or may be of usual construction. As herein shown, the main frame 3 of the harness contains heddles 4 and is provided at its lower edge with suitable downwardly extending link connectors 5 which support an equalizing bar 6, which in turn is provided with the usual staple-shaped connection 7.

The body of the connector is composed of two sections, a lower section 8 and an upper section 9. The lower section 8 of the body is provided at its lower end with an aperture 10 in which is received the end of the treadle 1. The bottom edge 11 of the aperture 10 is desirably shaped to be received within the usual notches 12 in the treadle. The treadle 1 is actuated by suitable cams, which are not shown, or by any other actuating means. The upper end of the section 9 is provided with a laterally extending arm 17 preferably formed integral with the upper end of the section. Upon the end of the arm 17 is formed a downwardly projecting vertical arm 18 spaced from and extending parallel to the upper end of the section 9 and forming a vertical recess 19 therewith, in which is received the lateral portion 20 of the staple 7. The lateral portion 20 may be provided with a reinforcing shoe 21 which may be of special construction or may be the shoe which is used in connection with a strap employed for connecting the treadle with the harness.

The lateral arm 17 is provided with a vertical screw-threaded aperture 22 within which is received an adjusting screw 23 the lower end of which engages the shoe 21 upon the staple. The screw 23 is desirably provided with a lock nut 24 by means of which the screw is locked in any desired position. The harness 2 is thus attached to the connector by reason of the position of the staple 7 within the recess 19 and by the engagement of the staple or the reinforcing shoe 21 with the adjusting screw 23.

To adjust the connector the bolt 15 is loosened and the slack roughly taken up by relative movement between the two sections 8 and 9. This adjustment will be quickly and easily accomplished since it is not necessary at this time to introduce the final degree of tension. The bolt 15 is then tightened positively, locking the two sections together. Further and more accurate ad-

justment may then be made by moving the screw 23 downward. When the desired tension is reached the lock nut 24 is tightened, thus determining positively and infallibly the desired length 5 of the connector. Those familiar with the art will readily appreciate the advantage of the adjustment provided by the screw 23 since this adjustment may be made regardless of any pre-existing tension in the connecting elements which may be 10 either increased or decreased to the desired amount. The important point, however, is that in initially setting up the loom the coarse adjustment provided by the serrations 13 and 14 may be made with little effort, while the final tension 15 and proper position of the harness may be easily made thereafter by means of the screw 23.

The accurate setting of the loom harness becomes by means of this device so easily obtained that the loom operator is induced to maintain the 20 harnesses in exact adjustment, thereby insuring uniformly high quality in the product. An important point to be noted is the fact that the adjustment obtained by the screw 23 may be made independently of any other of the co-operating 25 elements of the loom, it being unnecessary to disconnect or change the position of any of the parts to accomplish the proper adjustment.

This device not only provides means for readily 30 and accurately obtaining the proper tension in the harness connecting elements, but also provides a means of accurately coordinating the motion of the harness and the extent of the shed produced thereby with the associated elements of the loom.

Obviously, readjustments are equally simple to 35 make. After a loom has been running for a considerable period of time its parts may have become slightly worn and it is often necessary to readjust the harness connectors. By means of 40 the present invention, this readjustment is done by means of the screws 23, it being unnecessary to let off completely the tension in the warps. In a multiple cam loom or a dobby loom employing 45 a large number of harnesses, it is especially difficult with the ordinary equipment to adjust the harnesses to present at all times a smooth even shed. The present invention reduces the labor of such adjustment to a minimum and insures accurate results.

Having thus described the invention, what is 50 claimed as new, and desired to be secured by Letters Patent, is:

1. In combination with a loom having harness 55 actuating means and a harness provided with a connecting staple projecting downwardly from the harness, a connector extending between the harness actuating means and said staple comprising a two-section longitudinally adjustable body, means for positively locking the two sec-

tions in adjusted position, means for securing the connector to the harness actuating means, a screw having threaded engagement with the upper end of the body and adjustable longitudinally thereof acting by engagement at its lower end 80 with the staple on the harness to adjust the effective length of the connector, thereby constituting a supplemental adjustment to the adjustment provided by the two-section body and means to flexibly attach the connector to the staple. 85

2. In combination with a loom having harness actuating means and a harness provided with a connecting staple projecting downwardly from the harness, a connector extending between the harness actuating means and the staple comprising a two-section longitudinally adjustable body, means for positively locking the two sections in adjusted position, means at one end of the body to connect it to said harness actuating means, a fixed vertical arm spaced from and in parallel relation to the other end of said body forming a vertical recess within which is received the lateral portion of said staple and a vertically disposed adjusting screw having threaded engagement with said body its lower end engaging the lateral portion of said staple and acting when adjusted to change the effective length of the connector thereby constituting supplementary adjustment to that provided by the adjustable body. 100

3. In combination with a loom having harness actuating means and a harness provided with a downwardly extending connecting staple, a connector extending between said harness actuating means and said staple comprising a longitudinally adjustable body having two sections the adjacent ends of which overlap, interengaging transverse serrations on the overlapping portions of each of said sections, means to lock said sections in adjusted position, means flexibly to connect the connector with the harness actuating means, an arm extending laterally outward from the upper end of said body, a vertical arm extending downwardly from the outer end of said lateral arm spaced from and in parallel relation to the upper end of said body forming a vertical recess therewithin which is received the lateral portion of said staple, a vertically disposed adjusting screw having threaded engagement with said lateral arm and having its lower end projecting into said recess engaging the lateral portion of said staple and acting when adjusted to change the effective length of the connector thereby constituting supplementary adjusting means to that provided by the adjustable body section. 115
